AUTOMATIC AUXILIARY FUEL PUMP SYSTEM

Howard A. Satterlee, Bryan, Ohio, assignor to
The Aro Equipment Corporation, Bryan, Ohio,
a corporation of Ohio

Application August 25, 1941, Serial No. 408,233

12 Claims. (Cl. 158—36.3)

1

My present invention relates in general to an automatic fuel pump system provided with a plurality of separate fuel sources wherein the contents from a plurality of fuel containers are automatically connected in predetermined order to a source of fuel consumption, such as an aeroplane engine or the like, the general features of such a system being shown in the David Samiran application Serial No. 261,542, filed March 13, 1939, and now matured into Patent No. 2,327,373.

One object of my invention is to provide such a fuel system wherein a manual fuel pump is eliminated, and an automatic electric pump is used in place of the usual hand pump.

Another object is to provide a system wherein the electric pump serves both the function of supplying fuel from a reserve fuel tank to the carburetor or fuel injector of the engine when starting the engine in order to afford proper operation of a fuel pressure switch and the function of supplying fuel to the engine when fuel through the engine driven pump of the system fails as a result of failure of fuel in a tank connected by an automatic selector valve with the engine driven fuel pump.

Another object is to provide in connection with an automatic selector valve controlled by a fuel pressure responsive switch, an electric operating circuit which causes operation of the electric fuel pump at the proper times, depending upon various cycles of operation of the fuel system occurring.

Still another object is to provide a reserve fuel tank from which the electric pump receives fuel and an automatic means to keep the reserve tank filled with sufficient fuel for a number of electric pump operations, regardless of the number of electric pump operations necessary during the functioning of the fuel system.

A further object is to provide the electric pump so connected with the fuel pressure switch that it is controlled thereby in conjunction with a manual switch operable upon starting of the engine to effect a slow rotation of the electric pump to prevent improper carburetor or fuel injector action, and, at the same time, fill the conduit system with fuel so that the engine is ready to start by the time its starting mechanism functions.

A further object is to provide an automatic fuel system wherein an electric pump automatically supplies fuel until such time as an engine driven pump supplies fuel at a predetermined and slightly greater pressure sufficient to operate the engine, whereupon the electric pump is cut off and remains idle until the engine is again started, or until such time as fuel from one source fails and a selector valve then operates to connect the carburetor or fuel injector with another source, the electric pump during the change-over period

2 supplying fuel for the requirements of the carburetor or fuel injector.

With these and other objects in view, my invention with respect to its features which I believe to be novel and patentable will be pointed out in the claims appended hereto. For a better detailed understanding of the invention, and further objects relating to details of economy of my invention, reference is made to the following description and to the accompanying drawings wherein such further objects will definitely appear, and in which:

Figure 1 is a diagrammatic view of a portion of a fuel system with an auxiliary fuel pump embodying my invention connected therein.

Figure 1a is a similar diagrammatic view of the remaining portion of the fuel system, Figure 1a being a continuation of Figure 1.

Figure 2 is a diagrammatic view of the fuel pressure switch of the system showing the parts in a different position as when the fuel system is functioning to supply fuel by the engine driven pump to the carburetor or fuel injector.

Figure 3 is a similar diagrammatic view showing the position of the fuel pressure switch when fuel pressure rises following a selector valve operation; and

Figure 4 is a sectional view on the line 4—4 of Figure 1 showing a by-pass valve arrangement.

On the accompanying drawings I have used the reference character C to indicate generally a carburetor or fuel injector. An air eliminator is indicated at AE, a fuel pressure switch at PS, an engine driven fuel pump at P¹, an electric fuel pump at P² and a strainer at S. A plurality of fuel sources, such as a main tank T¹, an auxiliary tank T², and a reserve tank T³, are connected by a selector valve SV with the strainer S.

The carburetor C has a fuel supply pipe 30 which feeds fuel through suitable passageways to a spray nozzle 31. The spray nozzle 31 opens only when the fuel is above a predetermined pressure, such as six pounds. The nozzle, by way of example, may have a diaphragm 32 responsive to the fuel pressure and opened against the bias of a spring 33. The nozzle then discharges atomized fuel into the air intake 34 of the carburetor C. Obviously, instead of the carburetor, the fuel may be supplied to a fuel injector such as now used in connection with aeroplane engines.

A conduit 35 is adapted to receive fuel either through a conduit 35 from the electric pump P² or through conduits 36 and 37 from the engine driven pump P¹. Between the conduits 36 and 37 the air eliminator AE is mounted, and between the air eliminator and the conduit 36 I provide a check valve 38. The air eliminator is fully described in the above referred to Samiran application, and includes, briefly, a housing 39 adapted to receive the fuel from the pump P¹ and to eliminate air and vapor therefrom through

a conduit 40 discharging back into one of the fuel tanks, such as T². The air and vapor flow is controlled by a float valve 41, the float thereof being indicated at 42. The valve 41 is adapted to seat in an opening 43^a when the float is raised. The air and vapor are further controlled by a disk-like vent valve 43 having a spring 44 backing it and set, for instance, at ten pounds pressure. The pressure at which the vent valve 43 opens is modified by pressure on the top of the valve disk, which pressure may be either atmospheric pressure through a conduit 45 or super-charger pressure where the engine is of supercharged type. In that case the outlet pressure of the supercharger is introduced through the conduit 45 to the top of the vent valve 43.

The carburetor C may also have an air eliminator float valve 41^a, the float being indicated at 42^a and the air and vapor eliminating conduit at 40^a connected with the conduit 40.

The selector valve SV includes a rotor 46 adapted to connect an outlet conduit 47 with any one of three or more inlet conduits such as 48, 49 and 50. The conduit 48 extends from the main fuel tank T¹ and the conduit 49 extends from the auxiliary fuel tank T². The conduit 50 connects with a stand pipe 51 in the reserve fuel tank T³ so that it can receive only a portion of the fuel therefrom, the remaining portion being left as a reserve for the electric pump P².

The selector valve SV is operated by a selector valve motor SM in a manner fully disclosed in Samiran Patent No. 2,275,471. Briefly, the operative connection between the motor SM and the selector valve rotor 46 includes a bevel pinion 52, a bevel gear 53, step-down gears 54 and 55, and a selector valve shaft 56. The bevel gear 53 may be clutched and declutched relative to the pinion 54 by a solenoid S² operative, when energized, to engage a toothed clutch element 57 with a similar toothed clutch element 58. The element 57 is slidably and non-rotatably mounted on a shaft 59 to which the gear 54 is secured, and the clutch element 58 is secured to the bevel gear 53. When the solenoid S² is energized it engages the clutch elements with each other.

The selector valve shaft 56 is shown extended to a dial 60 with which a hand lever 61 cooperates to manually operate the selector valve when necessary or desirable, and to indicate the position of the selector valve at all times.

The pressure switch PS is also disclosed in the last mentioned Samiran application, as well as in Samiran Patent No. 2,291,654, issued August 4, 1942. Briefly, it includes a diaphragm 62 subjected to the fuel pressure by means of a conduit 63 connected with the conduit 31. The diaphragm 62 is in the retracted position of Figure 1 under the bias of a spring 62^a when the engine is idle, and in the extended position of Figure 2 when fuel pressure has been built up, as to fourteen pounds. A carriage 64 is carried by the diaphragm 62 and, in turn, carries a pivoted arm 65 having a spring-extended bridging roller 66 to cooperate with a pair of switch contacts 67 and 68. A stationary stop pin 65^a contacts at times with the arm 65 to cause the roller 66 to bridge the contacts 67 and 68, as will hereinafter be described.

A solenoid S¹ also cooperates with the pivoted arm 65 by reason of its plunger 69 being normally in the extended position of Figure 1. Whenever the solenoid S¹ is energized the plunger 69 moves to a retracted position.

For controlling the solenoid S¹ a stop switch 75

SS¹ is provided which is operated by a cam 70 on the selector valve shaft 56. Another switch SS², which may be termed a "slow switch," is operated by a second cam 71 also on the selector valve shaft 56. The slow switch SS² is adapted to control the speed of the selector valve motor SM by permitting it to rotate at low speed when the slow switch SS² is open. In that case the current flows through a resistance R² to cut down the energization of the motor.

The engine driven pump P¹ has a by-pass return valve 72 which may be set for fourteen pounds. The electric pump P² has a similar by-pass return valve 73 which may be set for approximately eleven pounds. The pump P² has a second by-pass return valve 74 (see Figure 4) set at three pounds, or thereabouts. Passageways leading past the valve 74 are restricted for a purpose which will hereinafter appear.

For operating the pump P² an electric pump motor PM is provided. The pump P² receives fuel through a conduit 75 from the reserve fuel tank T³.

A circuit arrangement is provided for the various elements of the fuel system described and includes a source of electric current, such as a battery 12, grounded through a wire 10. A wire 13 extends to an ignition switch IS from which a wire 14 leads to the contact 67 of the pressure switch PS. The ignition switch IS is for the ignition system of the engine on which the fuel system is installed, a wire 14^a being the wire leading to the ignition mechanism.

The pressure switch contact 68 is connected by a wire 15 with one side of a selector switch SS³. The other side of the switch SS³ is connected by wire 16, 20 and 20^a to the slow switch SS², from the other side of which a wire 17 extends to one side of the selector valve motor SM. The other side of the selector valve motor is grounded. The wire 20 also connects the wire 16 with one side of the stop switch SS¹. The other side of the stop switch is connected by a wire 21 with the solenoid S¹, which also has one side grounded.

The selector switch SS³ is a toggle switch adapted to be manually moved to "off" position, and to be automatically moved to "on" position by a build-up of oil pressure in the oiling system of the engine. For this purpose a bellows chamber 16 is shown diagrammatically, having therein a pressure bellows 17. The bellows 17 may be collapsed by oil pressure from a conduit 78 against the bias of a spring 79. The conduit 78 leads to the pressure side of the oiling system of the engine. The bellows 17, upon contraction, extends a stem 80 to a position for engaging the toggle lever of the selector switch SS³ when it is in "off" position and moving it to the "on" position.

A wire 18 extends from the wire 15 to an auxiliary switch AS. The auxiliary switch is also a toggle switch and its toggle lever is connected, as by a shaft 77^a, with the toggle lever of the selector switch SS³ whereby they may both be manually moved to "off" position and will both be automatically moved to "on" position by a build-up of oil pressure. The auxiliary switch AS is connected by a wire 19 to the pump motor PM for controlling it and operating it at high speed when the switch is closed and current is being supplied to the wire 18. When the switch AS is open, an adjustable resistance R¹ is in the circuit of the motor, thus slowing it down.

The pump P^2 (at slow speed when the resistance R^1 is in series therewith) pumps fuel at a pressure slightly greater than three pounds, and the by-pass valve 74 maintains the delivered pressure at three pounds. The resistance R^1 is made adjustable so that it can be set to deliver fuel at a slightly higher pressure than the pressure at which the by-pass valve 74 is set.

When the auxiliary switch AS is closed, however, the pump motor PM rotates at maximum speed and delivers fuel at a pressure in excess of eleven pounds for which the by-pass valve 73 is set. Such fuel is delivered through a check valve 81 to the pipe 35 and from there through the conduit 30 to the carburetor C.

A lamp L is connected with the wire 15 to indicate to the pilot the flow of current through the pressure switch PS. A test switch TS is shunted across the pressure switch for the purpose of permitting the pilot to test the circuit, when desired.

A fuel pressure gauge 82 may be connected by a conduit 83 with the conduit 30 so as to indicate to the pilot the pressure being delivered to the carburetor C. A relatively small conduit 84 is also connected with the conduit 30 and extends to the reserve fuel tank T^3 . At its opposite end a float valve 85 is mounted, the float therefor being indicated at 86, and being operable to close the float valve when the float is rendered buoyant. The conduit 84 is provided for the purpose of supplying fuel to the reserve tank T^3 whenever the level therein recedes below that for which the float 86 is set. Thus I am constantly assured of an adequate reserve supply of fuel in the tank T^3 to supply fuel to the electric pump P^2 whenever it operates.

Practical operation

In the operation of the fuel system described, and of my auxiliary pump therefor, the pilot, when he desires to start the engine, must turn off the selector switch SS^3 , which also turns off the auxiliary switch AS. He then turns on the ignition switch IS. The pressure switch PS is in the closed position of Figure 1, due to the fuel pressure being at zero. Accordingly, current would be supplied to the selector valve motor SM if the selector switch SS^3 were not open, and thus cause operation of the selector valve at a time when it is unnecessary.

Closure of the ignition switch, besides supplying current for the ignition system of the engine, supplies current through the resistance R^1 to the pump motor PM. Accordingly, the pump P^2 will operate to pump the fuel to the carburetor, which would otherwise have to be pumped thereto by a hand pump. The electric pump, therefore, eliminates the operation of a hand pump being imposed upon the pilot. Since the pump motor PM is rotating slowly because of receiving current through the resistor R^1 , it will build up only slightly more than three pounds' pressure, and the excess fuel will be by-passed through the valve 74. The three pounds' pressure is insufficient for opening the nozzle 31 of the carburetor as it takes six pounds' pressure to open it.

The engine starter may now be operated, which will also cause the engine driven pump P^1 to operate. The pump P^1 will start building up pressure, and when such pressure exceeds six pounds it will open the nozzle 31, whereupon the engine will start and pressure produced by the pump P^1 will build up to fourteen pounds, at which the by-pass valve 72 is set. At thirteen pounds' pressure

the pressure switch PS opens (see Figure 2), thereby opening the circuit to the resistor R^1 and to the pump motor PM. Since the engine driven pump P^1 is now supplying fuel to the carburetor, operation of the pump P^2 is no longer necessary. The cut-off of the pressure switch PS will be indicated by the signal lamp L going out.

After the pressure switch PS has opened there will be a further build-up of oil pressure in the oil system of the engine, which will soon close the selector switch SS^3 and the auxiliary switch AS. The circuit to these switches, however, has been broken at the pressure switch so that no circuit is established at this time through switches SS^3 and AS. The fuel system will now function in the usual manner, the air eliminator AE eliminating air and vapor whenever such is present in the housing 39 until fuel raises the float 82 to close the valve 81. Such air and vapor will be eliminated only when its pressure is in excess of ten pounds, or whatever the pressure setting of the pressure control valve 43 is. The check valve 81 will prevent flow of the fuel in the wrong direction, and, likewise, when the pump P^2 is operating, the check valve 83 will prevent reverse flow of fuel into the air eliminator and the pump P^1 .

When the pilot stops the engine by opening the ignition switch IS the current is cut off to all parts of the circuit and the engine will stop, resulting in retraction of the stem 60 of the selector switch SS^3 to the position shown in Figure 1, and the fuel pressure in the line 63 will drop, resulting in the pressure switch PS receding to the position shown in Figure 1 and effecting bridging of the contacts 67 and 68 by the roller 66. Subsequently, the engine may again be started as already described.

Assume now that the engine is operating and the tank T^1 runs out of fuel. The selector valve operation will occur by reason of the fuel pressure in the conduit 63 receding to below thirteen pounds and thereby causing the carriage 64 to move to the position of Figure 1, effecting movement of the roller 66 from the position of Figure 2 to the position of Figure 1 by reason of the stop pin 65^a being engaged by the pivoted lever 65. A circuit is now established through the pressure switch and the selector switch SS^3 (now on, because the pressure of the oil system of the engine has been built up due to engine operation) to the solenoid S^2 and to the switches SS^1 and SS^2 . Energization of the solenoid S^2 causes its plunger 57^a to engage the clutch element 57 with the clutch element 58. The switch SS^2 , it will be noted, is open so that the current flows through the resistor R^2 and thus starts the selector valve motor at low speed. Soon after starting, the motor SM rotates the shafts 59 and 56 and the lobe on the cam 71 closes the slow switch SS^2 to shunt out the resistance R^2 and operate the selector valve motor SM at high speed. Thus the motor operates at high speed while changing from one selector valve position to the next, except adjacent the end of the positioning of the valve the slow switch SS^2 again is opened by the cam 71 and the final aligning of the port 46^a of the valve rotor 46 with the next port, such as 49, is accomplished slowly to permit the port to stop in exact registry as soon as the motor SM and the clutch solenoid S^2 are deenergized.

During this final aligning movement of the selector valve, fuel is being picked up from the tank T^2 by the pump P^1 , and thereby pressure is built up within the pressure switch PS. The switch carriage 54 will accordingly be carried

from the position of Figure 1 to the position of Figure 3, with the switch 66—67—68, however, still in closed position because the solenoid S¹ is in energized position (shown dotted in Figure 2 and by solid lines in Figure 3). The solenoid S¹ was energized by closure of the stop switch SS¹ through wire 21, and thus the Figure 3 position of the pressure switch assures completion of the selector valve change-over even though pressure has been built up in the switch PS. Finally, when the selector valve is in exact registry, the stop cam 70 will open the stop switch SS¹, thereby deenergizing the solenoid S² and causing its plunger 69 to move to the full-line position of Figure 2 for opening the switch PS.

Opening of the switch PS deenergizes the circuit to the selector valve motor SM through the selector switch SS³ and also deenergizes the solenoid S² to permit its core 57^a to return to its initial position or raised position. Deenergization of the clutch solenoid S² insures instant stopping of the selector valve without any possibility of over-run, as might occur if the selector valve were directly connected with the motor and thereby subject to motor over-run after the motor has been deenergized.

The purpose of the selector switch SS³, responsive to pressure in the oil system of the engine, is to insure that the engine must be started before current is supplied to the circuit of the selector valve motor SM. This is necessary because the pressure in the fuel system, and, consequently, in the pressure switch PS at the time of starting the engine, is too low, or, in fact, is substantially zero, and hence the switch PS will be in the closed position of Figure 1 to start the motor SM. This would result in the selector valve SV shifting to the next tank, and if the fuel pressure were still low it would shift on to the succeeding tank, even though the tanks were full of fuel. Such operation of the selector valve is unnecessary and desirable because during the shift from one position to the next, i. e., when the port 46^a is out of registry with any of the conduits 48, 49 and 50, there will be no fuel supply to the pump P¹.

The pump P² creates a pressure condition in the fuel system for initiating the starting of the engine, and also when the selector motor SM is energized the pump motor PM is also energized, but at its high speed, because the auxiliary switch AS is closed at that time due to normal operating oil pressure when the engine is running. Thus when the fuel system runs out of fuel from one tank and the selector valve motor is energized, the pump motor PM is also energized at its high speed to pump fuel from the reserve tank T³ through conduits 15, 35 and 30 to the carburetor at a pressure of eleven pounds. Due to the restriction of the passageways for the by-pass return valve 74 a little of this fuel will pass through the valve, but there can still be a build-up of enough pressure to exceed the eleven-pound pressure for which the by-pass return valve 73 is set. The eleven-pound pressure is sufficient to keep the carburetor C operating, as such pressure is in excess of that required to open the nozzle 31. Thus the pump P² also eliminates the necessity of having a relatively large air eliminator AE wherein a reserve supply of fuel is carried to feed the carburetor C while the selector valve is passing through a cycle of operation. The pump PM operates only at the times desired, i. e., when the pressure of the fuel should be built up at the beginning of engine operation and to supply the carburetor with fuel during a selector valve oper-

ation when there would be interruption in the fuel supply to the main pump P¹.

The stand pipe 51 makes it possible to use fuel from the reserve tank T³ after the main tank T¹ and all auxiliary tanks, such as T² and others not illustrated, have been exhausted; yet, if fuel is used from the reserve tank before some of the others are exhausted, there will still be some left for the operation of the pump P². I insure that there will always be a level of fuel slightly above the stand pipe 51 by returning some of the pumped fuel through the conduit 84 to the tank T³ and controlling it by the float valve 85.

With my arrangement the air eliminator can be considerably reduced in size so that its float mechanism need be large enough only to actuate the float valve, and, of course, the parts should be strong enough to withstand shock and vibration. While the pump P² operates to supply fuel at a time when the selector valve is changing from one position to the other, it does not interfere with operation of the selector valve, and also it does not, due to its particular hook-up in the circuit, permit the selector valve to operate when there is a fuel pressure drop due to the engine being stopped, rather than due to actual failure of fuel while the engine is operated. The resistance R¹ and the auxiliary switch AS are so arranged and so operated that the pump P² does not open the nozzle 31 of the carburetor when the engine is starting, but permits the pump P¹ to build up a pressure to accomplish this result. However, the pump P² operates at its high speed when the selector valve motor is energized, and at that time serves as a means to supply fuel for opening the nozzle 31 and causing the carburetor to continue to function, even though the pump P¹ is only pumping air. Such air, of course, is eventually eliminated through the eliminator AE, and as soon as it is eliminated the fuel pressure rises and opens the switch PS, thereby deenergizing the pump P² and deenergizing the circuit for the selector valve motor SM.

Having described one specific embodiment of my invention together with the operation thereof, I desire it to be understood that this form is selected merely for the purpose of facilitating disclosure of the invention rather than for the purpose of limiting the number of forms which it may assume. It is to be further understood that various modifications, adaptations and alterations may be applied to the specific form disclosed to meet the requirements of practice without in any manner departing from the spirit and scope of the present invention except as set forth in the claims appended hereto.

I claim as my invention:

1. An auxiliary fuel pump system comprising a plurality of fuel tanks, a main fuel pump for pumping fuel from said tanks to a fuel consuming device, a selector valve located between said tanks and said main fuel pump for selecting the tank from which fuel is taken, a fuel pressure switch communicating with the outlet of said main fuel pump for controlling said selector valve, an auxiliary fuel pump having an inlet connected to one of said fuel tanks and an outlet connected to said fuel consuming device, said auxiliary fuel pump having a high pressure by-pass and a low pressure by-pass from said outlet to said inlet, an electric motor for operating said auxiliary fuel pump, a circuit for said electric motor controlled by said fuel pressure switch, a resistance 75 for said motor to effect rotation thereof at slow

speed to cause said low pressure by-pass to function and said auxiliary pump to thereby deliver fuel at low pressure to said fuel consuming device, a switch for shunting said resistance to effect rotation of said motor at high speed to cause said high pressure by-pass to function and said auxiliary pump to thereby deliver fuel at high pressure to said fuel consuming device, said last switch being manually opened upon starting the operation of the fuel system, and means responsive to the operation of said fuel consuming device to automatically move said last switch to closed position.

2. An auxiliary fuel pump system comprising a plurality of fuel tanks, a main fuel pump and an auxiliary fuel pump for pumping fuel from said tanks to a fuel consuming device, a selector valve located between said tanks and said main fuel pump for selecting the tank from which fuel is taken by said main fuel pump, a fuel pressure switch communicating with the outlet of said main fuel pump for controlling said selector valve, an auxiliary fuel pump for pumping fuel from one of said tanks, an electric motor for operating said auxiliary fuel pump, a circuit for said electric motor controlled by said fuel pressure switch, a resistance for said motor to effect rotation thereof at slow speed to thereby deliver fuel at low pressure to said fuel consuming device, and a switch for shunting said resistance to effect rotation of said motor at high speed to thereby deliver fuel at high pressure to said fuel consuming device.

3. An auxiliary fuel pump system comprising a plurality of fuel tanks, a main fuel pump for pumping fuel from said tanks to a carburetor or the like, a selector valve located between said fuel tanks and said main fuel pump, an auxiliary fuel pump for pumping fuel from one of said tanks to said carburetor for selecting the tank from which fuel is taken by said main fuel pump, a fuel pressure switch communicating with the outlet of said main fuel pump for controlling said selector valve; an electric motor for operating said auxiliary fuel pump, and a circuit for said electric motor controlled by said fuel pressure switch.

4. In an auxiliary fuel pump system, a plurality of fuel tanks one of which is a reserve tank, conduits leading therefrom, a main fuel pump for pumping fuel from said tanks to a carburetor of an engine, an auxiliary fuel pump, a selector valve for selecting the tank from which fuel is taken by said main fuel pump, said selector valve having intakes connected with said conduits and an outlet connected with said carburetor, a fuel pressure switch communicating with the outlet of said main fuel pump for operating said selector valve, said auxiliary fuel pump having an intake conduit connected with said reserve tank and an outlet conduit connected to said carburetor, said auxiliary pump being connected with said fuel pressure switch to be operated thereby whenever said pressure switch operates said selector valve, a stand pipe in said reserve tank connected with one of said first conduits, one of the intakes of said selector valve being connected therewith, a return fuel pipe from said carburetor to said reserve tank, and a float valve for controlling the replenishing of said reserve tank with fuel from said return fuel pipe.

5. In an auxiliary fuel pump system, a plurality of fuel tanks one of which is a reserve tank, a main fuel pump for pumping fuel from said tanks to a carburetor or the like, an auxiliary fuel pump for pumping fuel from one of said tanks to said

carburetor, a selector valve located between said fuel tanks and said main fuel pump for selecting the tank from which fuel is taken by said main fuel pump, a fuel pressure switch communicating with the outlet of said main fuel pump for operating said selector valve, said auxiliary fuel pump receiving fuel from said reserve tank and delivering it to said carburetor upon operation of the auxiliary pump, said auxiliary pump being connected with said fuel pressure switch to be operated thereby whenever said fuel pressure switch operates said selector valve, a return fuel pipe from said carburetor to said reserve tank, and a float valve for controlling the replenishing of said reserve tank with fuel from said return fuel pipe.

6. An auxiliary fuel pump system comprising a plurality of fuel tanks, a main fuel pump, conduits from said tanks, a selector valve connected with said conduits and with said main fuel pump for selecting the tank from which fuel is taken, an auxiliary fuel pump connected with one of said tanks, a fuel pressure switch responsive to failure of fuel from the tank with which the selector valve is connected, said switch energizing a motor for the selector valve to change its position to select another fuel tank, said auxiliary fuel pump having an electric motor for operating the same, a circuit for said electric motor, an auxiliary switch and a resistance in said circuit shunt-connected with each other and both series connected with said fuel pressure switch, said motor rotating at slow speed when said last switch is in open position and at high speed when said last switch is closed to shunt said resistance out of circuit with said motor.

7. An auxiliary fuel pump system comprising a plurality of fuel sources, a main fuel pump for pumping fuel from the said sources to a carburetor or the like of an engine, an auxiliary fuel pump for pumping fuel from one of said tanks to said carburetor, a selector valve located between said fuel sources and said main fuel pump for selecting the tank from which fuel is taken by said main fuel pump, a fuel pressure switch communicating with the outlet of said main fuel pump for controlling said selector valve by closure of the switch when the fuel pressure fails, said auxiliary fuel pump being electric motor driven and having low and high pressure, excess pressure return valves, a circuit for the motor thereof in series with said fuel pressure switch, a resistance for said circuit to effect rotation of said motor at slow speed for delivery of fuel at low pressure to said carburetor, and a switch for shunting said resistance to effect rotation of said motor at high speed to deliver fuel at high pressure to said carburetor.

8. An auxiliary fuel pump system comprising a plurality of fuel sources, a main fuel pump for pumping fuel from one of said sources to a fuel-consuming device, an auxiliary fuel pump for pumping fuel from one of said sources to said fuel-consuming device, a selector valve located between said fuel sources and said main fuel pump for selecting the source from which fuel is taken, a fuel pressure switch communicating with the outlet of said main fuel pump for controlling said selector valve, said auxiliary fuel pump delivering fuel from said last-mentioned one of said sources directly to said fuel-consuming device, an electric motor for operating said auxiliary fuel pump, a circuit for said electric motor controlled by said fuel pressure switch, a resistance in circuit with said motor to effect

rotation thereof and of said auxiliary fuel pump at slow speed to thereby deliver fuel at low pressure to said fuel-consuming device, a switch for shunting said resistance to effect rotation of said motor and said auxiliary fuel pump at high speed to thereby deliver fuel at high pressure to said fuel-consuming device, and check valves between said pumps and said fuel-consuming device to prevent reverse flow of fuel through one of said pumps while the other one is functioning to deliver fuel to the fuel-consuming device.

9. An auxiliary fuel pump system comprising a plurality of fuel tanks, a main fuel pump for pumping fuel from said tanks through an air eliminator to a carburetor or the like of an engine having a carburetor fuel admission valve which opens only when the fuel to the carburetor exceeds a predetermined pressure, an auxiliary fuel pump for pumping fuel from one of said tanks to said carburetor, a selector valve located between said tanks and said main fuel pump for selecting the tank from which fuel is taken by said main fuel pump, a fuel pressure switch communicating with the outlet of said main fuel pump for controlling said selector valve, said auxiliary fuel pump having a high pressure excess pressure return valve and a low pressure excess pressure return valve, said low pressure excess pressure return valve being set to operate at a lower pressure than the carburetor valve, an electric motor for operating said auxiliary fuel pump, a circuit for said electric motor controlled by said fuel pressure switch, a resistance for said circuit to effect rotation of said motor at slow speed for delivery of fuel to said carburetor at a pressure low enough to prevent discharge of the fuel into the engine through the carburetor valve, a switch for shunting said resistance to effect rotation of said motor at high speed to deliver fuel at operating pressure to said carburetor, and check valves between said auxiliary pump and the carburetor and between said air eliminator and the carburetor to prevent reverse flow of fuel into the auxiliary pump when the main pump is properly delivering fuel and for preventing reverse flow of fuel into the air eliminator when the auxiliary pump is delivering fuel to the carburetor.

10. An auxiliary fuel pump system for an engine comprising a plurality of fuel tanks, a main fuel pump for pumping fuel from said tanks through an air eliminator to a carburetor or the like having a carburetor fuel admission valve that opens only when the fuel to the carburetor exceeds a predetermined pressure, an auxiliary fuel pump for pumping fuel from one of said tanks to said carburetor, a selector valve located between said fuel tank and said main fuel pump for selecting the tank from which fuel is taken by said main fuel pump, a fuel pressure switch communicating with the outlet of said main fuel pump for controlling said selector valve, an electric motor for operating said auxiliary fuel pump, a circuit for said electric motor controlled by said fuel pressure switch, a resistance for said circuit to effect rotation of said motor at slow speed for delivery of fuel to said carburetor at a pressure low enough for the carburetor valve to prevent discharge of the fuel into the engine, a switch for shunting said resistance to effect rotation of said motor at high speed to deliver fuel at operating pressure to said carburetor, and check valves between said auxiliary pump and the carburetor and between said air eliminator and the carburetor and opening toward the carburetor.

11. An auxiliary fuel pump system comprising a plurality of fuel tanks, a main fuel pump for pumping fuel from said tanks to a carburetor or the like having a carburetor fuel admission valve which opens only when the fuel to the carburetor exceeds a predetermined pressure, an auxiliary fuel pump for pumping fuel from one of said tanks to said carburetor, a selector valve located between said fuel tanks and said main fuel pump for selecting the tank from which fuel is taken by said main fuel pump, a fuel pressure switch communicating with the outlet of said main fuel pump for selecting the tank from which fuel is taken by said fuel pump, a fuel pressure switch communicating with the outlet of said main fuel pump for controlling said selector valve, an electric motor for operating said auxiliary fuel pump, a circuit for said electric motor controlled by said fuel pressure switch, a resistance for said circuit to effect rotation of said motor at slow speed for delivery of fuel to said carburetor at a pressure low enough for the carburetor valve to prevent discharge of the fuel into the engine, and a switch for shunting said resistance to effect rotation of said motor at high speed to deliver fuel at operating pressure to said carburetor.

12. An auxiliary fuel pump system comprising a plurality of fuel tanks, a main fuel pump for pumping fuel from said tanks to a carburetor or the like of an engine having a carburetor fuel admission valve that opens only when fuel to the carburetor exceeds a predetermined pressure, an auxiliary fuel pump for pumping fuel from one of said tanks to said carburetor, a selector valve located between said fuel tanks and said main fuel pump for selecting the tank from which fuel is taken by said main fuel pump, and a fuel pressure switch operative to close when the fuel pressure through said selector valve and from said main fuel pump fails due to failure of fuel from the tank with which the selector valve is connected, said switch energizing a motor for the selector valve to change its position to another fuel tank, said auxiliary fuel pump having an electric motor for operating the same, a circuit for said electric motor, an auxiliary switch and a resistance in said circuit shunt-connected with each other and both series connected with said fuel pressure switch, said resistance effecting rotation of said motor at slow speed for delivery of fuel from said carburetor to the engine at a pressure low enough for the carburetor valve to prevent discharge of the fuel thereinto when said auxiliary switch is in open position and to effect rotation of said motor at high speed to deliver fuel and operating pressure to said carburetor when said auxiliary switch is closed.

HOWARD A. SATTERLEE.
